UNITED STATES PATENT OFFICE

2,354,620

FUEL INJECTION TURBINE

John W. Smith, Philadelphia, Pa.

Application January 16, 1940, Serial No. 314,040

4 Claims. (Cl. 60—13)

The object of this invention is to devise a novel, supercharged, fuel injection turbine provided with constant volume for the ignition period.

The scavenging air enters a piston controlled port in one cylinder and is forced through piston controlled turbine nozzles into the turbine blades as an important means of air cooling the turbine blades and rotor.

With the foregoing in view, my invention comprehends a novel construction of a fuel injection turbine.

My invention further comprehends novel means for varying the constant volume period while the engine is running.

Other novel features of construction and advantage will hereinafter be described in the following description and the appended claims.

For the purpose of illustrating the invention, I have shown in the accompanying drawings a typical embodiment of it, which, in practice, will give satisfactory and reliable results. It is, however, to be understood that the various instrumentalities of which my invention consists can be variously arranged and organized and my invention is not limited to the exact arrangement and organization of these instrumentalities as herein set forth.

Figure 1 is a sectional elevation of a fuel injection engine embodying my invention, and illustrative of one type of construction by means of which my novel method may be utilized.

Figure 2 is an end elevation partly in section.

Figure 3 is a sectional elevation on an enlarged scale, showing a portion of the turbine, the section being taken on line 3—3 of Figure 1.

Figure 4 is a sectional view, on an enlarged scale, of a portion of the turbine.

Figure 5 is a section on line 5—5 of Figure 2.

Figures 6 to 9 inclusive are schematic views showing different periods of the cycle.

Similar numerals indicate corresponding parts.

Referring to the drawings:

1 designates a casing having outer anti-friction bearings 2 and inner anti-friction bearings 3 in which wobble cranks 4A and 4B are mounted. Each wobble crank has an external flange 5 engaging a thrust bearing member 6 which cooperates with roller bearings 7 to transmit motion to wobble members 8A and 8B. The wobble members 8A and 8B reciprocate piston valves 9A and 9B through ball and socket links 10. The wobble members 8A and 8B are prevented from rotating by guides 11 which are free to oscillate between working faces of segments 12 which are

a part of an annular ring 13, rotatably adjustable in the casing 1.

The piston valves 9A and 9B have their inner ends of such contour, that, when the piston valves 5 are at constant volume position, a substantially spherical combustion chamber 14 is formed. Each piston valve has a slot 15 in order to create a turbulence in combustion chamber 14, as shown by the arrows in Figure 1. Turbulence starts approximately 30° before constant volume period, therefore piston 9A has just completed 30° of turbulence movement, which takes place during the constant volume period. In view of the fact that turbulence started 30° before constant volume period, fuel injection may start 15° or 20° before constant volume period.

The fuel is injected into the combustion chamber during the turbulence period by a conventional spray nozzle inserted into an opening 16. 10 A tubular turbine shaft 17 has first and second stage impellers 18 and 19 mounted on it.

Scavenging and supercharging air enters air inlet 20 and follows the arrows in Figure 1, to impellers 18 and 19, therefrom to annular passage 21, and is forced through piston valve controlled port 22 at a predetermined pressure by means of the two-stage turbine compressor. A pipe 23 supplies a liquid cooling medium to annular cavity 24 of piston valve cylinder 25. The 15 supercharging and scavenging air in passage 21 is also cooled by the liquid cooling medium in the cavity 24.

Turbine rotor 26 is secured on tubular shaft 17 by bolts 27, and has impellers 28 and impellers 29. A cylinder 25 is provided with turbine nozzles 30 and 31 for impinging the kinetic energy of the gases in the turbine blades 32 of rotor 26.

The nozzles 30 and 31 are made as short as possible and are mathematically proportioned to complete expansion in the turbine nozzle within a predetermined period of time, see Figures 6 and 7.

One set of impellers 18, rotating in a suitable 45 annular casing 57, imparts a velocity to the air within the casing and represents one stage of generating velocity and pressure to the air. Rotating in a casing 58 is a set of second stage impellers 19 for raising the air pressure above the first stage. The air is directed from the first stage impellers 18 by stationary vanes 59 to the second stage impellers 19.

As shown in Figures 1, 2, 3 and 4, a novel cooling system is employed. Cooling air enters an 50 air inlet 33 for impellers 28 which force cooling

air through passages 34 to cool the turbine rotor and its blades.

Inlet 35 supplies cooling air to impellers 29 which force air through passages 36 for the same purpose. This air follows the direction of the arrows, on the turbine rotors as a cooling system, acts to lower the temperature of the annular exhaust cavity 37 and escapes with the turbine exhaust through outlet 38.

The turbine shaft 17 is journaled on shaft 39 secured to wobble crank 4A by bolts 40, and is connected with the wobble crank 4B by a fastening device 41 consisting of a bolt and sleeve. A pinion 42 on turbine shaft 17 drives an integral gear and pinion 43 journaled on shaft 44 carried by planetary yoke 45 fixed to wobble crank 4B by bolts 46. A pinion 47 of the gear and pinion 43 engages a stationary rack 48, and represents the means for transmitting power from the turbine rotor to the power shaft.

A cam 49 by means of a roller 50 oscillates rocker 51 which actuates a conventional fuel injection pump through push rods 52.

The constant volume period is regulated by a lever 53 having a ball shaped and extending into an aperture in the ring 13. A movement in the direction of A, Figure 2, increases the constant volume period by advancing wobble member 8A to position A and a movement in the direction of B decreases the period of constant volume, by retarding wobble member 8A to position B.

The combustion chamber is formed by an annulus 54 and the juxtaposed ends of the piston valves.

56 are counterweights for controlling balance.

In Figures 6, 7, 8, 9, the dotted lines 55 indicate crank pin positions relative to the positions of piston valves.

The turbine cycle, within the expansion period, in Figure 6, starts as piston valve 9A uncovers port 39, and, in Figure 7, piston valve 9A has fully uncovered port 32, and the turbine cycle has been completed.

In crank pin position 55, for piston valve 9B in Figure 6, the turbine cycle is beginning, and, in Figure 7 it is completed. Figure 8 shows the relative position of piston valves at the start of supercharging; and Figure 9 shows the relative position of valves at the completion of supercharging and the start of the compression period which merges into constant volume.

The piston valve positions for constant volume are shown at the top of Figure 1, and the piston valve positions for scavenging are shown at the bottom of Figure 1.

Constant volume turbulence in the combustion chamber 14, see Fig. 1, is a fundamental condition created by slot 15 in piston 9A or 9B by the mechanism as shown.

The duration of constant volume is controlled by lever 53.

During the compression period, the position of piston in Fig. 1 shows that it has completed the action of forcing the air into the combustion chamber 14 through the slot 15 which has functioned as the receiving passage for the combustion chamber 14.

During the constant volume period, the withdrawal of piston 9A from the combustion chamber 14 causes the receiving passage to function as the exit passage.

Piston 9B forces into the combustion chamber the constant volume air which is expelled through the slot 15 in the piston 9A.

Having thus described my invention, what I claim as new and desire to secure by Letters Patent is:

1. In a fuel ignition turbine, engine cylinders having air admission and turbine nozzle ports, a compressor feeding air under pressure to said air admission ports, opposed piston valves in said cylinders controlling the air admission ports and turbine nozzle ports, fuel injecting means, a turbine receiving potential energy from said turbine nozzle ports, actuating mechanism for said piston valves to establish a constant volume period providing for the completion of combustion at a constant volume and within a given time, and means to vary the constant volume period while the engine is running.

2. In a fuel ignition turbine, engine cylinders having air admission and turbine nozzle ports, a compressor feeding air under pressure to said air admission ports, opposed piston valves in said cylinders controlling the air admission ports and turbine nozzle ports, fuel injecting means, a turbine receiving potential energy from said turbine nozzle ports, actuating mechanism for said piston valves to cause one of said piston valves to reach the end of its compression stroke prior to its opposed piston valve and to establish a constant volume period providing for the completion of combustion at a constant volume and within a given time, and means to adjust said actuating mechanism, while the engine is running, to increase or decrease the constant volume period.

3. In a fuel ignition engine, engine cylinders having air admission ports and exit ports, a compressor supercharging said air admission ports, opposed piston valves in said cylinders one of which controls an air admission port while the other controls an exit port, fuel injecting means, means to actuate said piston valves to establish a constant volume period, and means to regulate the actuating means for the piston valves, while the engine is running, to increase or decrease the constant volume period.

4. In a fuel injection turbine, means to start and complete combustion at a constant volume, and means to vary the period of constant volume while the turbine is running.

JOHN W. SMITH.
